UNITED STATES PATENT OFFICE.

GIUSEPPE F. PINSUTI, OF NEW YORK, N. Y.

BOTTLE-STOPPER.

1,140,062.

Specification of Letters Patent. Patented May 18, 1915.

Application filed August 27, 1914. Serial No. 858,853.

To all whom it may concern:

Be it known that I, GIUSEPPE F. PINSUTI, a citizen of the United States, residing in the borough of Manhattan, city, county, and State of New York, have invented an Improvement in Bottle-Stoppers, of which the following is a specification.

My present invention relates to a bottle stopper, and is an improvement upon the bottle stopper shown and described in my co-pending application, Serial No. 694,446, filed May 1, 1912, for Letters Patent for a similar invention.

The object of this invention is to reduce the cost of manufacture, by simplifying the construction and eliminating all unnecessary parts, and the bottle stopper made in accordance with the present invention preferably comprises a body member having a chamber therein with ports communicating with the chamber from the exterior of the stopper, a valve seat, a light flexible valve, and a valve controller actuated through gravity by its own weight, the construction and operation of all of which will be herein-after more particularly described.

In the drawing, Figure 1 is a sectional longitudinal cross section of a bottle stopper embodying my present invention. Fig. 2 is a cross section on line 2, 2, Fig. 1. Fig. 3 is a perspective view of the light flexible valve employed in the stopper. Fig. 4 is a view similar to Fig. 1, showing the parts of the stopper in their inverted positions. Fig. 5 is also a central longitudinal cross section illustrating another form of the invention. Fig. 6 is a transverse cross section of a modified form of the valve controller, and Figs. 7 and 8 are central longitudinal cross sections illustrating other forms of the invention.

Referring to the drawing, and particularly to Figs. 1 to 4, inclusive, my improved bottle stopper comprises a body member 10, made of any suitable material and in any desired configuration. Interiorly, the body member 10 is provided with a chamber 11. In one end, preferably the outer end of the body member, there is a port 12, in a portion of which there is a wall 13, with ports 14 therethrough, the ports 12 and 14 making communication with the chamber 11 from this end of the body of the stopper. The opposite end of the body member is open and fitted with a plug 15, which, when placed in position, bears against a shoulder 16, pro-

vided interiorly of the body member. Extending through the plug 15 are ports 17, which provide communication with the chamber 11 from this end of the stopper. 60 As illustrated, a portion of the plug 15 is of reduced diameter, and adapted to enter the mouth of the neck of a bottle, as indicated at 18, with the shoulder formed between the parts of the plug flush with the end of the 65 body member.

Surrounding the plug 15, and lying between the adjacent ends of the body member 10, and the end of the neck of the bottle, I prefer to employ a gasket 19, and the stopper, in this form of the invention, is preferably secured to the neck of the bottle by a band 20, which extends around the same, suitably gripping the body member 10, and also the outer surface of the neck of the bottle. The inner surface of the plug 15 is indicated at 21. This, while forming one of the walls of the chamber 10, is also a valve seat. Within the chamber 10, I employ a valve 22. This is preferably square, as 80 clearly indicated in Fig. 3, and is made of sheet cork, thin rubber, or other similar and equally flexible material. Also within the chamber 11 I employ a valve controller 23. The base of the controller is preferably circular in outline, and in spaced positions on its periphery, there are ribs 24 providing the intervening recesses or passage-ways 25 for escape of the contents of the bottle. 85

The walls forming the sides of the chamber 11 are suitably tapered, and the faces of the ribs 24, on the controller member, are inclined at the same angle, the inclined side walls forming the chamber 11 being indicated at 26. 90

In their normal or initial positions, the parts of the hereinbefore described stopper are those indicated in Fig. 1, wherein the valve controller 23 bears against the outer surface of the valve 22 and causes the opposite surface thereof to rest against the valve seat 21. In pouring the contents of the bottle therefrom, the bottle is inverted, as is customary, and the valve controller 23 then falls to the opposite end of the chamber 11, 105 carrying with it the valve 22, because of the adhesion between these members, due to the moisture accumulated thereon, either from within or without the bottle, it being noted that the contact surface between the valve 110 22 and the valve controller 23 is considerably greater than the contact surface be-

tween the valve and its seat. After the contents of the bottle, or a portion of the same, has been poured therefrom, and when righting the bottle, the valve controller will rest 5 against the adjacent inclined walls of the chamber 11, and when, or approximately when, the bottle reaches a horizontal position, the valve controller will slide on these inclined walls and will return to its initial 10 position, carrying the valve with it and thereby seating the same.

It is here to be noted that inasmuch as the base of the valve controller is circular, and the valve is rectangular and the diameter of 15 the base of the controller is approximately equal to the distance between the opposite corners of the valve, all the corners of the valve will project an appreciable distance beyond the recessed portions of the base of 20 the controller, so that, with the bottle in an inverted or partially inverted position, in attempts to refill the same, the inflowing fluid will strike against these projecting corners, separating the valve from the controller, without necessarily moving the latter, and will carry the valve to its seat, independently of the controller, in order to 25 close the ports 17 in the plug 15 and thereby prevent the fluid from flowing into the 30 bottle.

By reference to Fig. 5, it will be seen that I may dispense with the use of the plug member 15, utilizing the end of the neck of the bottle 27 as a valve seat. In this construction, the neck of the bottle, at its extremity, is of reduced diameter, providing a shoulder 29, between which and the adjacent member of the body member 10 a gasket 28 is employed for forming an air and 35 liquid-tight joint between the parts.

In some instances, it may be advisable to increase the bearing surface of the valve seat, when the extremity of the neck of the bottle is employed for this purpose, and in 40 so doing, the end of the neck of the bottle may be provided with cross members 34, between which there are ports or openings 35 for permitting the contents of the bottle to be poured therefrom. In this construction, as will also be understood, it is necessary to grind the extremity of the neck of the bottle, in order to obtain a uniformly flat surface for the valve seat. Also, as shown in Fig. 6, in some instances, I may construct 45 the valve controller in two parts, the outer end of the main part 30 being recessed to receive a removable member 31, which is normally held in position by frictional contact. The purpose of constructing the valve 50 controller member with separating parts is to prevent the possibility of holding the valve controller out of its place, in attempts to refill the bottle, by means of adhesive substance, or otherwise, because in such attempts, as will be readily apparent, the re-

movable member might be so held, and if so, the main portion of the controller would be freed therefrom to operate the valve. Furthermore, as clearly indicated in Fig. 7, the inclined periphery of the valve controller 23 70 may be a uniformly even surface, and in this instance the walls forming the inclined sides of the chamber 11, in the stopper 10, are provided with suitably spaced ribs 32 with intervening recesses or passages 33 for 75 the discharge of the contents of the bottle. In this construction, as well as that shown in Fig. 8, the operation of the parts are the same as that described in connection with the form of the invention shown in 80 Figs. 1 to 4, inclusive.

In order to insure the proper seating of the valve, and to prevent the accumulation of any deposit thereon, due to the evaporation of the material which the bottle may 85 contain, I prefer, in all instances, to provide a recess surrounding the valve seat. In the form of invention shown in Figs. 1 to 4, inclusive, this recess is between the plug 17 and the adjacent surface of the body 90 member, and is indicated at 36, whereas in the other forms of the invention this recess lies between the outer surface of the neck of the bottle adjacent the valve seat and the adjacent portion of the body member. Also, 95 by reference to Fig. 5, it will be seen that in use the port 12, in the outer portion of the body member, is closed by a cork 37, or other stopper, and in order that the cork may be readily grasped, in order to remove 100 the same, it may also be so placed in the port as not to extend beyond the end of the body member. The outer portion of the body member may be recessed, as indicated at 38. As will also be understood, the cork, 105 so placed, does not protrude, and consequently will not become accidentally displaced. In this construction, I may combine the valve and valve controller as an integral device, or dispense entirely with 110 the use of the compressible valve. Also by reference to Fig. 7, it will be seen that the removable member, associated with the controller, may be a thin disk 39, made of mica or other similar and equivalent material 115 fitted within a recess provided for the same in the upper or outer surface of the controller. Furthermore, in instances where the thin disk is employed, the wall 13 is provided with a projection 40, which prevents 120 the disk 39 from leaving the recess in the controller without in any wise interfering with the operation of the controller.

I claim as my invention:

1. A bottle stopper comprising a body 125 member having a chamber with which communication is provided through a port in the stopper, the walls of which are inclined and diverge from the said port, a flat valve seat, a flat valve, and a valve controller 130

adapted to bear against the said valve and to normally maintain the same against its seat, the said valve being movable independently of the said valve controller, the 5 periphery of the said valve controller being tapered at an inclination corresponding to that of the walls of the chamber of the stopper so that the said valve controller may slide on the said walls in returning to the 10 position in which it normally maintains the valve against its seat.

2. A bottle stopper comprising a body member having a chamber therein with which communication is provided through 15 a port in the stopper, the walls of which chamber are inclined and diverge from the said port, a flat valve seat, a flat valve, a valve controller having a flat base adapted to bear against the said valve to normally maintain the same against its seat and to slide 20 against the said inclined walls of the stopper, and a removable member normally held in position frictionally in a recess provided therefor in the outer portion of the said 25 valve controller.

3. A bottle stopper comprising a body member having a chamber therein with which communication is provided through a port in the stopper and adjacent which a 30 projection extends from the said body member into the said chamber, a valve seat, a compressible valve, a valve controller adapted to normally maintain the said valve against its seat and to slide on the walls of 35 the said chamber, and a removable member held frictionally in position in a recess provided therefor in the outer portion of the said valve controller and prevented from being removed from its said recess by the 40 aforesaid projection.

4. A bottle stopper comprising a body member having a chamber therein with which communication is provided through a port in the stopper and the walls of which

are inclined, diverging from the said port, 45 a flat valve seat, a flat compressible valve, a valve controller having a flat base adapted to bear against the said valve, the periphery of the said valve controller being tapered at an inclination corresponding to 50 that of the inclined walls of the stopper so that the said valve controller may slide on the said inclined walls to its seated position, and a removable member held frictionally in position in a recess provided therefor in 55 the outer portion of the said valve controller.

5. A bottle stopper comprising a body member having a chamber therein with a port providing communication between the said chamber and the outer end of the said 60 body member, a flat valve seat, a flat compressible valve, a valve controller having a flat base adapted to bear against the said valve and normally maintain the same in position against its seat, and a removable 65 member normally held in position frictionally within a recess provided therefor in the outer side of the said valve controller.

6. A bottle stopper comprising a body member, having a chamber with which communication is provided through a port in the stopper and the walls of which are inclined and diverge from the said port, a flat valve seat, a valve member with the periphery tapered at an inclination corresponding 70 to that of the walls of the said chamber so that the said valve member may slide on the said walls in returning to its normal position, and a removable member normally held frictionally in the outer portion of the 75 said valve member.

Signed by me this 15th day of August, 1914.
